UNITED STATES PATENT OFFICE.

OSCAR WILLIAM HANSON, OF SALINA, KANSAS.

HEADLIGHT-DIMMER.

1,273,778.

Specification of Letters Patent. Patented July 23, 1918.

Application filed February 8, 1918. Serial No. 215,955.

To all whom it may concern:

Be it known that I, OSCAR W. HANSON, a citizen of the United States, residing at Salina, in the county of Saline and State 5 of Kansas, have invented certain new and useful Improvements in Headlight-Dimmers; and I do declare the following to be a full, clear, and exact description of the invention, such as will enable others skilled 10 in the art to which it appertains to make and use the same.

My invention has for its principal object to provide an extremely simple and inexpensive, yet an efficient head light dimmer, 15 so constructed as to prevent breakage of the electric bulb of the head light even though said globe may be extremely close to the lens in rear of which the device is used.

20 A further object is to so construct the dimmer as to confine the rays of light to the roadway, to furnish sufficient light a distance from the car, and yet prevent such light from being projected sufficiently high 25 to interfere with the vision of approaching pedestrians or others.

A still further object is to provide a dimmer which will soften the light rays so that drivers and others approaching the head 30 lights equipped with the invention will find the rays less blinding as they approach, and thus any small interfering effect which these rays may have upon the vision will be decreased as the machine is approached or 35 approaches, as the case may be.

With the foregoing general objects in view, the invention resides in the novel construction and arrangements of parts therein described and claimed and shown in the 40 accompanying drawing in which:

Figure 1 is a vertical section of a head light equipped with the dimmer; and,

Fig. 2 is a front view of the dimmer.

In the drawing, the numeral 1 designates 45 the substantially parabolic reflector of a head light, said reflector being located in a casing 2 provided with a lens 3 and a retaining ring 4 for holding said lens in place. At the center of the reflector 1 is 50 the usual electric bulb 5.

The improved dimmer is formed of a metal disk 6 stamped to form a small central ring 7, a peripheral ring 8, a plurality of horizontal slots 9 decreasing in width 55 from the upper to the lower edge of the disk, and an equal plurality of flat reflector

vanes 10 extending rearwardly from the lower edges of said slots, said vanes being formed by the metal struck from the slots and therefore decreasing gradually in width 60 toward the lower edge of the device. The angle between the vanes 10 and the disk also varies from acute at the upper edge of the device to substantially right angular at the lower edge thereof. Due to the central ring 65 7, no vanes exist at the center of the dimmer and consequently there is no danger of breaking the bulb 5 by contact therewith.

The dimmer is clamped between the inner side of the lens and its seat with the 70 vanes 10 extending rearwardly and most of them inclining upwardly, and when so applied, the device will serve to direct the upper reflected rays of light downwardly 75 onto the roadway and will prevent projection thereof at a height to interfere with the vision of pedestrians and drivers of other vehicles. The open space at the center of the dimmer is not of disadvantage although exposing the bulb 5, since it is the 80 strong reflected rays and not the direct rays that produce undesirable results on the vision.

The invention, although simple and inexpensive, possesses great advantages, these 85 advantages being first, that the dimmer is so constructed as not only to confine the rays of light to the roadway or prevent them from being projected sufficiently high as to interfere with the vision of approaching 90 pedestrians or drivers but also, and as a more important consideration, to furnish sufficient light farther ahead in the road. Second, pedestrians or others approaching the car equipped with these dimmers will 95 find the rays of light growing less blinding and offensive as they approach the dimmer. In other words, although the dimmers accomplish the desired purpose in preventing interference with the vision of those 100 approaching them, such interference as does exist decreases as they approach the dimmer.

I claim:

1. A head light dimmer comprising a 105 small central ring, a peripheral ring, short vertically spaced horizontal vanes extending between the two rings, and longer vertically spaced horizontal vanes spanning said peripheral ring above and below said central ring, all of said vanes extending rearwardly.

2. A structure as specified in claim 1, said vanes decreasing in width from the upper to the lower edge of the device.
3. A structure as specified in claim 1, said vanes varying their angular relation to the plane of said ring from acute at the upper edge of the device to substantially right angular at the lower edge thereof.
4. A structure as specified in claim 1, said vanes decreasing in width and increas-

ing their angle to the plane of the rings from the upper to the lower portion of the device.

In testimony whereof I have hereunto set my hand in the presence of two subscribing 15 witnesses.

OSCAR WILLIAM HANSON.
